Primary Examiner — Austin Murphy(74) *Attorney, Agent, or Firm* — Wood, Herron & Evans,
LLP**CLAIM**The ornamental design for a body of portable computer, as
shown and described.**DESCRIPTION**FIG. 1 is a top front perspective view of a body of portable
computer showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.
